US00D991790S

(12) **United States Design Patent** (10) **Patent No.:** **US D991,790 S**
(45) **Date of Patent:** **** Jul. 11, 2023**

(54) **BEVERAGE BOTTLE**

(71) Applicant: **Sire Spirits, LLC**, New York, NY (US)

(72) Inventor: **Curtis J. Jackson, III**, New York, NY (US)

(73) Assignee: **Sire Spirits, LLC**, New York, NY (US)

(*) Notice: This patent is subject to a terminal disclaimer.

(**) Term: **15 Years**

(21) Appl. No.: **29/717,437**

(22) Filed: **Dec. 17, 2019**

(51) LOC (14) Cl. **09-01**

(52) U.S. Cl. **D9/566**; D9/567; D9/544

(57) **CLAIM**

The ornamental design for the beverage bottle as shown and described.

DESCRIPTION

FIG. 1 is a front view of the beverage bottle of the present invention.

FIG. 2 is a rear view of the beverage bottle of the present invention.

FIG. 3 is a right side view of the beverage bottle of the present invention.

FIG. 4 is a left side view of the beverage bottle of the present invention.

FIG. 5 is a top view of the beverage bottle of the present invention.

The oblique lines used in the drawings are shown to represent a translucent material.

The broken lines of FIGS. 1-5 illustrate portions of the beverage bottle that form no part of the claimed design.

1 Claim, 5 Drawing Sheets
